UNITED STATES PATENT OFFICE.

HENRY A. WEIHMAN, OF PHILADELPHIA, PENNSYLVANIA, ASSIGNOR TO SIMONS, BRO. & COMPANY, A CORPORATION OF PENNSYLVANIA.

DESIGN FOR A HUMIDOR FOR TOBACCO-CASES.

No. 40,105.

Specification for Design.

Patented June 29, 1909.

Application filed March 17, 1909. Serial No. 484,056. Term of patent 7 years.

To all whom it may concern:

Be it known that I, HENRY A. WEIHMAN, a citizen of the United States, residing at Philadelphia, in the county of Philadelphia, State of Pennsylvania, have invented a new, original, and ornamental Design for a Humidor for Tobacco-Cases, of which the following is a specification, reference being had to the accompanying drawing, forming part thereof.

In the drawing Figure 1 is a plan view of humidor embodying my improved design; Fig. 2 is a side elevation of the same; and Fig. 3 is an end view of the same.

I claim:

The ornamental design for a humidor for tobacco cases, as shown.

HENRY A. WEIHMAN.
